(57) CLAIM

The ornamental design for a wine holder, as shown and described herein.

DESCRIPTION

FIG. 1 illustrates a perspective view of a bottle holder according to one embodiment of my design;
FIG. 2 illustrates a front view of the bottle holder;
FIG. 3 illustrates a back view of the bottle holder;
FIG. 4 illustrates a left side view of the bottle holder;
FIG. 5 illustrates a top view of the bottle holder;
FIG. 6 illustrates a bottom view of the bottle holder;
FIG. 7 illustrates a perspective view of the bottle holder;
FIG. 8 illustrates a perspective view of the bottle holder according to another embodiment of my design;
FIG. 9 illustrates a front view of the bottle holder;
FIG. 10 illustrates a back view of the bottle holder;
FIG. 11 illustrates a Left Side view of the bottle holder;
FIG. 12 illustrates a top view of the bottle holder;
FIG. 13 illustrates a bottom view of the bottle holder; and,
FIG. 14 illustrates a perspective view of the bottle holder. Those portions of the wine holder shown in broken lines and the text in FIGS. 8, 9, and 14 are included for illustrative purposes only and form no part of the claimed design.
